UNITED STATES PATENT OFFICE.

ANDREW H. REED, OF FULLERTON, CALIFORNIA.

INSERTER AND ELEVATOR FOR STANDING VALVES.

1,334,117.

Specification of Letters Patent. Patented Mar. 16, 1920.

Application filed June 24, 1919. Serial No. 306,380.

To all whom it may concern:

Be it known that I, ANDREW H. REED, a citizen of the United States, residing at Fullerton, in the county of Orange and State of California, have invented a new and useful Inserter and Elevator for Standing Valves, of which the following is a specification.

This invention embodies in a single device means for inserting and elevating standing valves, and an object of the invention is to provide an inserter and elevator which is constantly in position on the standing valve and lower end of the pump plunger so that the standing valve can be inserted in the well by lowering the plunger into the working barrel, and so that the standing valve can be withdrawn by pulling the plunger from the working barrel.

Another object is to produce a device of this character from which the standing valve may be suspended and which, after the standing valve is seated, will automatically become disengaged so that the gripping member may be withdrawn, leaving the standing valve in its seat.

Another object is to provide a device of this character which can be readily lowered and then turned through an angle of a certain number of degrees by turning the sucker rod to cause engagement of one of the elevator members with the other elevator member on the standing valve so that raising of the first named elevator member will cause lifting of the standing valve from its seat.

Another object is to eliminate use of the ordinary Garbut rod or similar device entailing first withdrawal of the pump plunger and then lowering of a cable into the well to remove the standing valve.

Another object is to produce a device of this character which will be positive in operation.

Other objects and advantages will appear in the subjoined detailed description.

The accompanying drawings illustrate the invention.

Figure 1 is a side elevation of the invention, one member thereof being shown in section on line indicated by $\alpha^1-\alpha^1$, Fig. 2. The invention is shown suspended from a fragment of a pump plunger and a standing valve is shown suspended by the invention from the pump plunger ready for inserting in the well or withdrawing therefrom.

Fig. 2 is an elevation from the left of Fig. 1, the parts being in position for causing relative rotation between the two members of the invention to disengage one of 60 said members from the other. The pump plunger is not shown in this view.

Fig. 3 is a view analogous to Fig. 2, excepting that the gripping member is shown in vertical mid section in the position it 65 occupies when the pump plunger is first lowered to engage the stem or is ready for raising to the pumping position after the standing valve has been inserted, and a portion of the standing valve is broken away 70 to contract the view.

Fig. 4 is a sectional elevation of the gripping member on line indicated by $\alpha^4-\alpha^4$, Fig. 3.

Fig. 5 is a plan section on line indicated 75 by $\alpha^5-\alpha^5$, Fig. 1.

Fig. 6 is a plan section on line indicated by $\alpha^6-\alpha^6$, Fig. 2.

Fig. 7 is a plan section on line indicated by $\alpha^7-\alpha^7$, Fig. 1.

Fig. 8 is an inverted plan section on line indicated by $\alpha^8-\alpha^8$, Fig. 1.

There is provided a gripping member 1 which may be, for example, of cylindrical construction as shown in the drawings. The member 1 is provided with screw-threads 2 or other suitable means for connection with the plunger of the pump with which the invention co-operates, a fragment of the lower end of a pump plunger being indicated at 3 in Fig. 1. If the plunger 3 is of the type having a receiving valve at its lower end the plunger portion 3 will be connected with and extend below the lower end of the cage of said receiving valve. In such event it is clear that when the pump plunger 90

is in action its lower valve will approach to within a comparatively slight distance of the standing valve which is indicated at 4. The plunger 3 and standing valve 4 form 100 no portion of the invention but merely co-operate therewith.

The gripping member 1 is provided with one or more openings 5, the upper edges of which form slanting abutments 6. In the 105 drawings there are two openings 5 and the slants of the abutments 6 are opposed to one another when both are viewed from one side. The abutments 6 are adapted to engage the upper end of a head 7 which forms the upper extremity of a stem 8 that is permanently screw-threaded into or otherwise fas-

tened to the standing valve 4 as clearly shown in Figs. 1 and 2. The head 7 forms a shoulder or shoulders 9 on the stem 8. In the drawings two such shoulders are shown. 5 These shoulders 9 are adapted to be engaged by abutments 10 formed by the lower edges of the openings 5. The standing valve 4 is suspended by the stem 8 from the gripping member 1 when the shoulders 9 rest 10 upon the abutments 10, as in Fig. 1.

The lower portion of the bore of the gripping member 1 forms a cylindrical mouth 11, and extending upwardly from said mouth to the upper end of the gripping member 15 and axially thereof is a slot 12 which is narrower in cross section than the diameter of the mouth 11 but of the same length in cross section as said diameter. At the junction of the mouth 11 and slot 12 are formed shoulders 13 on opposite sides of the bore, said shoulders extending reversely aslant to one another, when viewed from one side, and forming abutments adapted to engage the upper end of the head 7 so that, in event of 20 the gripping member 1 being lowered upon the stem 8 with the slot 12 turned cross-wise to the elongate head 7, the gripping member 1 will be rotated sufficiently to allow 25 said head to enter the slot 12.

30 The invention operates as follows: The gripping member 1 will be connected with the lower end of the pump plunger 3 and, when it is desired to insert the standing valve 4 in the well, said standing valve will be provided with the stem 8 and said stem will be inserted in the slot 12 of the gripping member 1 and then the standing valve will be rotated sufficiently to bring the shoulders 9 into the openings 5. Then the standing 35 valve will be lowered to bring the shoulders 9 to rest upon the abutment 10. Then the plunger with the standing valve suspended therefrom will be lowered into the pump tubing, not shown, until the standing valve rests upon the seat, not shown, provided for it at the lower end of the working barrel, not shown.

When the standing valve strikes the seat, the pump plunger will be lowered farther 50 thus causing the head 7 to engage the abutment 6 and, owing to the abutment 6 being constructed spirally of the member 1, said member will be caused to rotate until the head 7 comes into alinement with the upper portion of the slot 12.

The standing valve 4 may now be hammered securely into its seat by alternatively raising and lowering the pump plunger so as to cause the lower end of the gripping member to strike the upper end of the standing valve 4. After the standing valve 4 has been hammered into place, the plunger will be raised to withdraw the gripping member 1 from the stem 8. The plunger may then be operated in the usual manner to effect the

pumping operation, the plunger at the lower end of its stroke just clearing the stem 8.

When for any reason it becomes desirable to remove the standing valve from the well, the pumping operation will be stopped and the pump plunger will be lowered to cause the gripping member 1 to telescope upon the stem 8. During this lowering operation, if the slot 12 happens not to be in perfect alinement with the head 7, the end portions of 70 said head will engage the shoulders 13 and said shoulders, because of their extending spirally on the inner face of the gripping member, will cause the gripping member, pump plunger and sucker rod to rotate until 75 the head 7 is so alined with the slot 12 that the head will enter said slot. The pump plunger will then be lowered sufficiently to bring the openings 5 adjacent to the head 80 85 and then the sucker rod, not shown, connected to the plunger will be turned through an angle of 90° to cause the member 1 to be turned so that the head 7 will extend into the openings 5. Then the plunger will be raised, to cause the abutments 10 to engage 90 the shoulders 9 and to pull the standing valve from its seat and suspend said valve from the member 1 and stem 8. Then the plunger will be raised from the well to elevate 95 the standing valve thus suspended from the plunger.

It is noted that there can be no uncertainty about engaging and disengaging the stem 8 with the gripping member 1, for the member 1 is lowered upon the stem 8 until 100 the member 1 rests on the standing valve 4 as shown in Fig. 3 and then all that the operator need to do is to give the sucker rod a quarter turn and hoist away on the sucker rod; and when the valve is being inserted 105 the operator simply allows the sucker rod to descend until the member 1 strikes upon the seated standing valve thus to cause the abutments 6 to ride upon the head 7 so as to turn the member 1 to position for raising 110 free from the stem.

The invention is not limited in its broader phases to the exact details of construction shown in the drawings and described above, but includes such changes and modifications as lie within the spirit and scope of the appended claims.

I claim:

1. In a device of the character described, a stem adapted to be connected with a standing valve, and a gripping member adapted to be connected with a pump plunger and engageable with and releasable from the stem, the stem and gripping member having co-operating means to cause rotation of the gripping member out of stem-engaging position when the gripping member is lowered from gripping position.

2. In a device of the character described, a stem having a shoulder and adapted to be

connected with a standing valve, and a gripping member adapted to be connected with a pump plunger and provided with an abutment adapted to engage the shoulder when the gripping member is turned to one position and to be free of said shoulder when the gripping member is turned to a different position, the stem and gripping member having coöperating means to cause rotation 10 of the gripping member out of stem-engaging position when the gripping member is lowered from gripping position.

3. In a device of the character described, a stem adapted to be connected with a 15 standing valve, and a gripping member adapted for connection with a pump plunger and operative in one position to engage the stem and operative to a different position to engage the stem and operative to a different 20 position to release the stem, the stem and gripping member having coöperating means to cause rotation of the gripping member out of stem-engaging position when the gripping member is lowered from gripping 25 position.

4. In a device of the character described, a stem adapted to be connected with a standing valve, and a gripping member adapted for connection with a pump plunger and 30 operative when turned to one position to suspend the stem and operative when turned to a different position to release the stem, the stem and gripping member having coöperating 35 means to cause rotation of the gripping member out of stem-engaging position when the gripping member is lowered from gripping position.

5. The combination with a pump plunger and a standing valve, of a stem connected 40 with the standing valve, and means on the plunger operative by turning of the plunger in opposite directions to engage and disengage the stem, the stem and gripping member having coöperating means to cause rotation 45 of the gripping member out of stem-engaging position when the gripping member is lowered from gripping position.

6. In a device of the character described, a stem adapted to be connected with a stand-

ing valve and having a shoulder, and a gripping member adapted to be connected with a pump plunger and having an abutment to engage the shoulder to support the stem when the gripping member is turned to one position, the gripping member and stem having means whereby lowering of the gripping member relative to the standing valve will turn the gripping member to another position.

7. In a device of the character described, a stem adapted to be connected with a standing valve and terminating at its upper end in a head and having a shoulder, and a gripping member adapted to be connected with a pump plunger and having an abutment to engage the shoulder to support the stem when the gripping member is turned to one position, the gripping member having a slanting abutment to engage the head when the gripping member is turned to said position and is lowered relative to the standing valve.

8. In a device of the character described, a stem adapted to be connected with a standing valve and terminating at its upper end in a head and having a shoulder, and a gripping member adapted for connection with a pump plunger and having an abutment to engage the shoulder to support the stem when the gripping member is turned to one position, the gripping member having a slanting abutment to engage the head when the gripping member is turned to said position and is lowered relative to the standing valve, and the gripping member having a slot to guide the head to the last named abutment and having a slanting shoulder at the lower end of the slot adapted to engage one end of the head when the gripping member is lowered so as to cause turning of the gripping member into alinement with the head.

Signed at Los Angeles, California, this 19th day of June, 1919.
